UNITED STATES PATENT OFFICE.

THEODORE D. DAVIS, OF SYRACUSE, AND JOHN M. WALDRON, OF SOUTH OTSELIC, NEW YORK.

IMPROVEMENT IN HARVESTERS.

Specification forming part of Letters Patent No. 34,097, dated January 7, 1862.

To all whom it may concern:

Be it known that we, THEODORE D. DAVIS, of Syracuse, in the county of Onondaga and State of New York, and JOHN M. WALDRON, of South Otselic, in the county of Chenango and State of New York, have invented a new and useful Improvement in the Cutting Apparatus of Harvesting-Machines; and we do hereby declare that the following is a full, clear, and exact description of the same, reference being had to the accompanying drawings, making part of this specification, in which—

Figure 1 is a plan of a portion of our improved cutter. Fig. 2 is a vertical longitudinal section of the same (on a larger scale) at $x x$, Fig. 1. Fig. 3 is a transverse section of the same at $y y$.

Similar letters of reference indicate corresponding parts in the several figures.

The nature of our invention consists in an improved manner of attaching a set of movable cutter-blades to the cutter-bar, as herein-after explained.

A represents the cutter-bar.

B B B are a set of movable blades, formed with tapering heels, as shown in Fig. 1, and fitting in dovetails in the bar A, as shown in Fig. 2.

a' are hooked lugs, projecting upward from the bar A, and confining a wedge-shaped longitudinal rod, C, which is passed endwise between and beneath them. The smaller end of the said rod passes through a flange, a, upon the end of the bar A, and is threaded to receive a nut, c. The rod C bears upon the upper surface of the blades B and against protuberances b b b upon their heels, and thus secures them in their dovetail seats. The end blade, B', may be perforated, as shown, to pass over the eye E, to which the connecting-rod

is attached, and the rod C may pass through the said eye above the blade. The successive front lugs, a, are formed with the faces farther in front of the center of the bar, to accommodate the increasing width of the bar C. By this means the rear edge of the said rod is always parallel with the bar, and thus bears equally upon the protuberances b of all the blades, so as to tighten them all simultaneously and equally. The blades, with the exception of that which fits over the eye E, are (in practice) counterparts of each other, so that each will fit equally well in any place.

If it be needful to grind, repair, or replace any of the blades B, the nut c is removed and the rod C withdrawn. The blades will rest in their dovetails until taken out. When the blades are replaced, as desired, the rod C is again inserted, and, being drawn up by the nut c, presses the blades into position and holds them firmly backward within their dovetails, the latter keeping the blades from rising.

Having thus described our invention, what we claim as new, and desire to secure by Letters Patent, is—

Securing movable blades in dovetail grooves in the cutter-bar by means of a tapering rod, C, operating in connection with lugs a and protuberances b, substantially as explained.

The above specification of our improved cutter-bar for harvesters signed this 12th day of November, 1861.
